LENS FOR RADIO FREQUENCY WAVES

Filed April 22, 1944

UNITED STATES PATENT OFFICE

2,415,352

LENS FOR RADIO-FREQUENCY WAVES

Harley A. Iams, Princeton, N. J., assignor to
Radio Corporation of America, a corporation
of Delaware

Application April 22, 1944, Serial No. 532,381

16 Claims. (Cl. 250—11)

1

This invention relates to lenses for radio frequency waves and more particularly to such lenses in which the wave reflections from the surfaces are reduced.

It is known that radio frequency waves may be reflected and refracted. Reflections or refractions of radio waves occur when a wave traveling through a medium reaches a discontinuity in the medium or goes from one medium into another in which its velocity is different. If the surface or object in the path of the wave is composed of non-conductive material, both reflection and transmission with refraction may occur depending upon the angle between the direction of propagation and the reflecting surface, and upon other factors which do not require discussion here.

Lenses for focusing radio frequency waves have been made of materials such as pitch, paraffin, and other insulators. The abrupt change from the dielectric constant of the medium of propagation to the dielectric constant of the lens produces an undesired reflection of the waves. The instant invention relates to the reduction of such undesired reflections.

One of the objects of the invention is to provide means for reducing the undesired reflection from the surface of a radio frequency lens. Another object is to provide an improved lens for radio waves of ultra high frequency. Another object is to provide a lens including reflection reducing surfaces whereby radio waves will be transmitted with less loss. An additional object is to provide an improved lens with a skeletonized surface for minimizing the reflection of radio frequency waves.

The invention will be described by referring to the accompanying drawing in which Figs. 1 and 2 are plan and section views, respectively, of one embodiment of the invention; Figs. 3 and 4 are plan and section views, respectively, of a radio frequency lens disposed between conductive members; Figs. 5 and 6 are plan and section views, respectively, of a biconvex lens including reflection reducing coatings; Figs. 7, 8 and 9 are plan, section views and a detailed section view, respectively, of a biconvex lens including a skeletonized surfaces; and Fig. 10 is a sectional view of a modification of the invention.

Referring to Figs. 1 and 2, a lens including a flat core 1 of wave refracting material such as "Micalex" is constructed with one curved surface 3 and one plane surface 5. By way of example, the dimensions are shown for a lens having a focal length of 17½ inches (measured from the straight edge) which was used to form a

2

line image of a scene illuminated with radiation having a frequency of 24,000 megacycles. The core material has a dielectric constant of 6.1. Coatings 7 and 9, consisting of "Lucite" or polystyrene having a thickness of approximately one quarter wave length in the coating material, are cemented or otherwise secured to the effective surfaces 3, 5 of the lens. The dielectric constant of the coating material should be the square root of that of the core material; since the dielectric constant of polystyrene is 2.5, it is well suited for coating "Micalex." In the case of the described lens, a substantial increase in transmission and a substantial reduction in undesired reflections were observed when radio waves of a frequency of 24,000 megacycles were applied. The image appears in the focal line represented by the dash line 11.

The lens described in the foregoing paragraph was inserted between a pair of conductive sheets 13, 15, preferably spaced by ½ wavelength or less. The sheets may be curved to form an aperture 17 which may be disposed otherwise than in geometric alignment with the effective surface 7 of the lens. The conductive sheets guide the radio waves toward the lens and from the lens to the focal line 11. The lens may be used for transmission by applying the wave energy at the open end of the sheets which may be shaped or bent to conform to the focal line.

In place of the section of plano-convex lens of Figs. 1 and 2, the invention may be applied to a biconvex lens as illustrated in Figs. 5 and 6 or 7 and 8. By way of example, a lens 19 was formed of "Micalex." The following dimensions are given by way of example rather than limitation: diameter 14 inches, radius of each face 40 inches, and focal length 13 inches. The coatings 21 and 23 should be made of an insulator having a dielectric constant of the order of 2.5 and a thickness substantially equal to a quarter wave length of the applied radio frequency waves as measured in the insulator. Since this thickness of the reflection reducing coatings is based upon normal incidence, it follows that the coating will not minimize reflections at all angles. For incidence other than normal, the ideal thickness is somewhat greater, being

$$\frac{1}{\cos \theta}$$

times a quarter wavelength in the coating material, where θ is the angle of incidence.

Instead of using a coating material having an effective thickness of a quarter wave length, 55 whereby the wave and the component which

would otherwise be reflected cancel, the arrangement illustrated in Figs. 7, 8 and 9 may be used to minimize reflections. This approach is particularly useful when a coating material having the desired dielectric constant is not available. In this arrangement, the surface layer of the lens is "skeletonized" by forming holes or grooves of the order of a quarter wave length deep. The holes 25 or grooves are preferably arranged so that several are disposed per wave length. Under these conditions the surface is skeletonized by removing a volume of the surface layer approximately equal to

$$\frac{1}{\sqrt{E+1}}$$

where E is the dielectric constant of the material. In the case of "Micalex," $E=6.1$; therefore the material to be removed equals 29% of the total surface layer. In the case of polystyrene, $E=2.5$ and the material to be removed equals 39% of the surface layer.

Another method of reducing the reflection is to avoid abrupt changes in dielectric constants. In a lens such as illustrated in Figs. 1, 2, 3 and 4, the reflection may be reduced by tapering the effective surface as shown in Fig. 10. The ideal length d of the taper may be determined from the equation

$$d = \frac{\alpha(\lambda_2 - \lambda_1)}{2(\log \epsilon\mu)}$$

where λ_2 =wave length in air, λ_1 =wave length in material of lens, μ =index of refraction of material, and α =any integer. For polystyrene and radio waves having a length of approximately $\frac{1}{2}$ inch in air, the reflection was found to fall steadily as d was increased from zero to about $\frac{3}{10}$ inch, and to be negligible for any length over $\frac{3}{10}$ inch.

In a lens as illustrated in Figs. 7 and 8, reflection may also be reduced by the use of tapered grooves, instead of the holes as shown. In this case, there should preferably be two or more grooves per wave length, and the depth should be as indicated in the preceding paragraph.

Thus the invention has been described as an improved lens for radio frequency waves. The reflections are reduced by applying a coating to the lens surface, or by skeletonizing the surface layer. The undesired reflections may also be reduced by tapering the effective surfaces of the lens, i. e., by tapering the surfaces which reflect the radio waves into the medium from which the waves have come.

I claim as my invention:

1. An ultra high frequency device consisting of an electric lens of a wave refracting material and a reflection reducing surface disposed on at least one effective surface of said lens.
2. An ultra high frequency device consisting of an electric lens of a wave refracting material having substantially parallel sides and a reflection reducing surface disposed on at least one effective surface of said lens.
3. An ultra high frequency device consisting of an electric lens of a wave refracting material and a reflection reducing coating disposed on at least one effective surface of said lens.
4. An ultra high frequency device consisting of an electric lens of a wave refracting material having substantially parallel sides and a reflection reducing coating disposed on at least one effective surface of said lens.
5. An ultra high frequency device consisting of

70
75
80
85
90

an electric lens of a wave refracting material and a surface having an effective thickness of an odd number of quarter wave lengths of said waves, disposed on at least one wave impinging surface of said lens whereby the reflection of said waves from said surfaces is reduced.

6. An ultra high frequency device consisting of an electric lens of a wave refracting material and a coating having an effective thickness of an odd number of quarter wave lengths of said waves in said coating, disposed on at least one wave impinging surface of said lens whereby the reflection of said waves from said surfaces is reduced.

10 7. An ultra high frequency device consisting of an electric lens of a wave refracting material having at least one curved surface and a skeletonized layer disposed on said curved surface and having an effective thickness of an odd integral number of quarter wave lengths of the applied electric waves whereby the reflection of said waves from said surface is reduced.

20 8. An ultra high frequency wave focusing device consisting of an electric lens of a wave refracting material having substantially parallel sides and at least one curved surface and a pair of conductive elements disposed parallel to each other, parallel to said surfaces and extending beyond said lens and away from said curved surface.

30 9. A device of the character of claim 8 in which the pairs of conductive elements are curved in the region extending away from said curved surface.

35 10. A device of the character of claim 8 in which a reflection reducing coating is disposed on said curved surface.

11. An ultra high frequency device consisting of an electric lens of a wave refracting material having at least one curved surface and having parallel sides and means for reducing the index of refraction of the material on said curved surface and having an effective thickness of an odd number of quarter wave lengths of the applied electric waves whereby the reflection of said waves from said surface is reduced.

40 12. An ultra high frequency wave focusing device consisting of an electric lens of a wave refracting material having substantially parallel sides and at least one curved surface and a pair of conductive elements disposed parallel to each other, parallel to said surfaces and extending beyond said lens in at least one direction.

13. An ultra high frequency wave refracting device consisting of wave refracting material having substantially parallel sides five or more wave lengths long perpendicular to the direction of motion of the wavefront placed between parallel conducting sheets separated by $\lambda/2$ or less.

55 14. An ultra high frequency device consisting of an electric lens of a wave refracting material and a reflection reducing surface, said surface including at least one projecting portion tapering along the axis of the lens.

60 15. An ultra high frequency device consisting of an electric lens of a wave refracting material and a reflection reducing surface, said surface including at least one projecting portion tapering along the axis of the lens in accordance with the equation

$$d = \frac{\alpha' \lambda_2 - \lambda_1}{2(\log \mu)}$$

in which d =the length of the taper, λ_1 =wave length in material of lens, λ_2 =wave length in air,

μ =index of refraction of material, and α =any integer.

16. A radio wave device consisting of a material having a characteristic defined by the equation $n=\sqrt{\epsilon'}$ where n =index of refraction and ϵ' =dielectric constant and a surface layer having an effective depth substantially equal to an odd integral number of quarter wave lengths of the applied waves and in which ϵ' =not less than $\frac{4}{\alpha}$ at the frequency of the applied waves.
